CHILD'S COSTUME SNOWSUIT OR THE LIKE

Charles Samuel Voss, New York, N. Y.

Application January 14, 1948, Serial No. 143,732

Term of patent 3½ years

(Cl. D3—17)

To all whom it may concern:

Be it known that I, Charles Samuel Voss, citizen of the United States of America, residing at the city of New York, in the county of New York and State of New York, have invented a new, original, and ornamental Design for a Child's Costume Snowsuit or the like, of which the following is a specification, reference being had to the accompanying drawing, forming part thereof.

The single figure of the drawing shows a child's costume snowsuit or the like embodying my design, with the body, hood and gloves shown in disassembled relation; one glove being shown with its palm side up and the other with the back side up.

The back of the snowsuit is of conventional design.

I claim:

The ornamental design for a child's costume snowsuit or the like, substantially as shown and described.

CHARLES SAMUEL VOSS.
